RUDOLF VON FROMMER, OF BUDAPEST, HUNGARY

BREECH-BOLT MECHANISM FOR SPORTING GUNS

Application filed October 16, 1929, Serial No. 399,998, and in Hungary October 20, 1928.

This invention relates to a breech bolt mechanism for sporting guns. The invention is characterized by the arrangement of a sleeve on the shaft of the locking bolt actuating key the said sleeve being acted upon by the locking spring, which is preferably made in the form of a spiral spring. The said key shaft and sleeve are of such construction that their coupling may not be effected otherwise than by mounting them into the breech body. For facilitating the assembling and the dismounting of the parts the said spiral spring acting upon the said sleeve on the key shaft is so arranged that while one end thereof is acting upon the sleeve the other end is supported by a spring casing which may be easily inserted into and extracted from the gun.

In the accompanying drawing one form of the breech bolt mechanism according to the invention is shown by way of example.

Fig. 1 shows the key, made of two parts, assembled in the breech body.

Figs. 2 and 3 show the two portions of the key shaft, each for itself.

Figs. 4 and 5 are different elevations of the key.

Fig. 6 shows the key mounted in the breech body together with its actuating spring and the casing of the latter, in a horizontal sectional view.

The key 1 is provided with the conventional square hole 2 (Fig. 4) into which the squared end 4 of the shaft 3 is snugly fitting. The two parts are interconnected by means of the screw 5. On the shaft 3 there is arranged a lug 6 which actuates the locking bolt 7 in a known manner. The upper bolt 8 is operated by the notch 9 of the key 1, in which engages the lug 10 of the said bolt 8 (Figs. 1 and 5). Mounted on the shaft 3 there is a sleeve 11, the nose 12 of which fits into the notch 14 of the key 1, whereby a connection between the sleeve and the key is established.

The spiral spring 16 is mounted in a case 25 which is held in the cavities 23 and 24 of the breech body 21 by the projections 19 and 20. For assembling the spring casing 25 in the breech body there are arranged in the latter two introducing grooves 27 and 28 (Fig. 1) which are positioned at 90° with respect to

the cavities 23 and 24. The projections 19 and 20 are inserted into these grooves and are then turned into the cavities 23, 24. Of course, a loose connection between the spring casing 25 and the breech body 21 may be established in any other way.

The spring 16 acts upon the shoulder 18 of the sleeve 11 through the intermediation of the pressure piece 17 and tends to rotate the same in the direction of the arrow shown in Fig. 6. Since the sleeve 11 is coupled to the key 1 and the latter is connected to the shaft 3, the spring 16 will swing the key 1 as well as the shaft 3 in the same direction. By the swinging of the key 1 towards the right, the two bolts 7 and 8 are withdrawn in a well known manner, the spring 16 being at the same time tensioned. Upon releasing the key 1 the spring will swing the same back thereby again locking the bolts.

The assembling of the breech bolt mechanism described is effected in the following manner:—

The bolt 7 is first introduced into the breech body, hereupon the sleeve 11 is pushed into the breech body downwards from the top and then the shaft 3 is introduced upwards from the bottom. The upper bolt 8 is now inserted, the key 1 mounted and screwed to the shaft 3 by the screw 5.

Having described my invention I claim:—
In a breech bolt mechanism for sporting guns, locking bolts, a key for operating the said locking bolts and having a shaft, a sleeve on the said shaft coupled to the said key and having a shoulder, a spring casing connected to the breech body, a locking bolt actuating spiral spring contained in the said spring casing, the said actuating spring acting upon the said shoulder to move the locking bolts into their locking position.

In testimony whereof I have affixed my signature.

RUDOLF VON FROMMER.
